LANDON R. CALVERT, OF NEWARK, NEW JERSEY, ASSIGNOR TO WESTINGHOUSE LAMP COMPANY, A CORPORATION OF PENNSYLVANIA

HERMETICALLY-SEALED PUMP

Application filed February 16, 1927. Serial No. 168,562.

This invention relates to double acting fluid pumps and more particularly to a pump of such type employed in gas purification systems.

5 In the manufacture of electrical devices employing gas filled envelopes and particularly those containing a gas filling such as argon, nitrogen and other inert gaseous mixtures, it is essential that the gases be entirely 10 free from contamination. In the case of argon, for example, the same must be free from hydrogen and oxygen which have a detrimental effect upon the operation of the devices in which the gas is to be used. In the 15 use of argon gas, it is not possible to secure such gas in a sufficiently pure state for use in an electrical device as above mentioned and systems have, therefore, been used in which the argon gas is passed through a 20 suitable catalyst and through scrubbing or cleaning agents until eventually stored in a drum for subsequent use as the environment in sealed envelopes of various types of electrical devices.

25 In systems of the above character, it is necessary to provide some means for maintaining a circulation of the gas and to pump the gas into a suitable container at a substantial pressure for convenient use. As heretofore 30 employed, the pumps were of such type that it was impossible to avoid a contamination of the gas during the pumping operation, thus in a measure, defeating the very purpose of the gas purification system.

35 The pumps referred to as heretofore being employed, usually included a sealing medium of a viscous fluid such as castor oil. The gases to be purified necessarily come in contact with the sealing medium and during the 40 pumping operation were often churned up with the oil and became impregnated with the vaporized medium such as hydrocarbon vapors which were detrimental to the usefulness of the gas.

45 An object of the present invention is, therefore, to provide a gas purification system in which the purified gas may be stored at substantial pressure without contamination.

50 Another object of the invention is to pro-

vide a pump applicable to such system as a hermetically sealed part thereof.

Another object of the invention is to provide a hermetically sealed duplex pump for creating a difference in pressure at opposite 55 sides of a closed circuit.

Other objects and advantages will be more fully understood as the description proceeds.

In carrying out the present invention, I provide a hermetically sealed pump which is 60 applied to a closed circuit and constitutes a part thereof to cause a steady circulation of a fluid. The pump is so constructed that no physical connection exists between the interior of the pump and the atmosphere, thus 65 avoiding the possibility of leaks and a contamination of the circulating medium.

Furthermore, the pump is so constructed that no possibility of excessive pressure can 70 occur even though the system might accidentally be closed, the pump acting to rise to a predetermined point and to remain at a constant pressure even though the outlet may be closed. Furthermore, the pump is of such 75 internal construction as to avoid maintenance or attention and may have an indefinite operative life since it is so constructed as to be substantially free from wear.

For the purpose of giving one practical embodiment or application of the present invention, the same is described in connection with a gas purification system and will be more clearly understood by reference to the accompanying drawings in which:

Fig. 1 is a front elevational view of the 85 pump embodying the present invention;

Fig. 2 is a side elevational view of the pump shown in Fig. 1;

Fig. 3 is a perspective detail view showing a flexible pipe connection employed in the 90 present pump construction;

Fig. 4 is a diagrammatic elevational view of the pump partly in section; and

Fig. 5 is a schematic representation of the 95 gas purification system showing the application of the present pump thereto.

Referring to Fig. 1, a pump indicated as a whole by the reference numeral 9 is constructed in accordance with the present invention comprising a pair of cylinders 10 and 100

11, each of which is half filled with mercury 12 and 13. The cylinders are mounted upon a rockable cross-member 14 having a bearing 15 journaled on a shaft 16. The said shaft may be held in a bearing 17 secured to a suitable supporting structure or table 18. The lower ends of the cylinders 10 and 11 may be connected by an arcuate communicating pipe 19 so that normally the levels of the mercury columns 12 and 13 will be the same and a tipping or oscillation of the cross-member 14 will cause a change in the said levels, causing the mercury in the respective cylinders to act as pistons.

15 Motion for actuating the cross-member 14 may be had through a link 21 connected to a crank 22 associated with a suitable speed reducing mechanism 23, motion being transmitted from any desirable source as a motor 24.

20 The upper walls of the heads of the cylinders 10 and 11 are provided with conductors 25 and 26 respectively which terminate in a common conductor 27 which extends downwardly and loosely encircles the shaft 16 in a plurality of convolutions 28 which terminate in a portion 29 of the conductor 27 constituting the outlet side of the pump connected with apparatus to be later described. The 25 encircling formation of the conductor 27 about the shaft 16 makes the same sufficiently resilient to permit a rocking of the structure support on the cross-member 14 without causing any fatigue of the metal. Conductors 25 and 26 are provided with chambers 31 and 32 respectively which may be filled with a suitable reducing material such as copper wool to prevent mercury vapor from passing through the system.

30 The other, or inlet side of the pump may be connected to the system in a manner to be later described through a conductor 33 (see Fig. 2) which encircles the shaft 16 by a series of convolutions 34 and extends upwardly in the form of a conductor 35 and is connected to a cross pipe 36 communicating with the conductors 25 and 26. The conductors 25 and 26 are provided with vertical check valves 37 and 38 respectively and the cross pipe 36, which is in fact an extension of the conductor 35, is provided with vertical check valves 39 and 41.

35 Although a pump as above described may be applicable for various uses, it is especially adapted as a "booster" in connection with a gas purification line such as diagrammatically shown in Fig. 5.

40 As illustrated, this system operates to purify argon gas which may be initially contained in a container indicated by the numeral 42. The gas then flows through pipe 43 to a compartment 44 containing a suitable catalytic agent, thence through a conductor 45 to compartments 46 and 47 containing suitable purifying agents such as

KOH and P_2O_5 , thence through conductor 48 to a compartment 49 which may contain copper or other suitable reducing agent, through a conductor 51 and another compartment 52 containing P_2O_5 . When the gas reaches this portion of the system, it is permitted to flow until a tank 53 becomes filled. A valve 54 may then be closed and the gas in the tank 53 may be circulated through a compartment 55 containing calcium and another compartment 56 containing P_2O_5 . For this purpose, the present pump 9 is provided as part of the system. Conductors 33 and 35 of the pump may then be connected to this circulating system, the conductor 35 being in communication with a conductor 58 leading back to the calcium tank 55 and the conductor 33 being connected by a conductor 59 to the tank 53. It will thus be evident that an operation of the pump will cause a circulation of the gas in the final purifying system until the gas in the tank 53 has reached a state of purification, whereupon it may be removed through pipe 61 for use. The state of purification of the gas may be determined by periodic tests.

45 When the present pump is applied to the above described system, its operation is as follows:

Assuming that the cross-member 14 is rocked so that the cylinder 10 is elevated as shown in Fig. 4, the mercury will then flow through the pipe 19 and the cylinder 10 will be partly or entirely emptied and the cylinder 11 filled or partly filled with the mercury. Suction will, therefore, be produced in the cylinder 10 and the check valve 37 will be closed. The check valve 39 will, however, be open admitting gas to the cylinder 10 and the pressure in cylinder 11 will close the check valve 41 and open the check valve 38, thus discharging gas through the pipe or conductor 27. When the cylinder 10 descends and the cylinder 11 is elevated, it is obvious that the mercury will flow into the cylinder 10. The pressure in the cylinder 10 will, therefore, close the check valve 39 and open the check valve 37 discharging gas through the outlet pipe while the suction in cylinder 11 will close the valve 38 and open the valve 41 thus producing a constant pumping operation.

50 The pressure exerted is directly in proportion to the length of the stroke produced from the link 21, that is, in proportion to the difference in height of the two mercury columns should the pump be working against a closed outlet. The volume discharged is, however, proportionate to the size of the cylinders 10 and 11 and the speed of the driving mechanism 24.

55 It will be evident that the pump alternates between producing suction and then producing compression and on the suction stroke the suction check valves 39 and 41 open on the discharge stroke the compression check

valves 37 and 38 open. Thus a continuous operation of the pump is attained and a constant flow of the pumped fluid is attained.

The simplicity of the present pump together with the low cost of manufacture makes the same of particular advantage in gas purification systems and it will be appreciated that if desirable, one pump may be used in connection with a system for purifying gas in the tank 53 while the valve 54 is closed and that during the operation of this pump, gas may be permitted to flow through a conductor 62 to a system including a tank similar to the tank 53 in which another pump may be located, thus when the tank 53 contains a supply of pure gas at the required pressure the same may be used and a valve 63 in the conductor 62 may be opened to fill another tank in another final purification system including another pump. It is obvious from the foregoing, that any number of pumps may be thus employed in the form of a battery, depending upon the capacity of the output desired.

It will readily be seen that by reason of the present invention a gas purifying system or any other system in which it is necessary to maintain a gas circulation, the gas may be caused to flow and stored at a substantial pressure for subsequent use without danger of contamination by the circulating means. In the present specific example in which argon is purified, considerable advantage is derived since the argon gas is merely circulated over a relatively small surface of the mercury and although it is found that the mercury vapor is practically negligible, a small amount of pure mercury vapor does not have any detrimental or contaminating effect upon the argon gas.

Although a preferred embodiment of the invention is shown and described herein, it is to be understood that modifications may be made therein without departing from the spirit and scope of the invention as set forth in the appended claims.

What is claimed is:

1. A pump comprising a cross-member, a compartment disposed at opposite ends of said member, a communicating passage between said compartments, a shaft for rockably supporting said support, inlet and outlet conduits for said compartments, said conduits being spirally disposed about said shaft to prevent detrimental stress in said conduits during a movement of said compartments.

2. A pump comprising a cross-member, means for pivotally supporting said member at a point intermediate the ends thereof, a compartment at each end of said cross-member, a communicating passage between said compartments, inlet and outlet conduits for said compartments, means for rocking said cross-member, said conduits having convoluted portions to prevent detrimental stresses

being imparted to said conduits during the movement of said cross-member.

3. A pump comprising a rocker-member, a plurality of compartments mounted on said member and movable therewith, a communicating passage between said compartments, a liquid body in said compartments and passage, means for actuating said rocker-member to cause a movement of said liquid body and alternately produce suction and compression in said compartments, inlet and outlet conduits for said compartments, said conduits having convoluted portions to prevent detrimental stresses therein during a movement of said rocker-member.

4. A pump comprising a plurality of compartments partially occupied by a metallic liquid, a cross-member for supporting said compartments at opposite ends thereof, a conductor communicating with said compartments, a shaft for pivotally supporting said cross-member, means for automatically rocking said cross-member to change the position of said liquid to create a vacuum alternately in said compartments, inlet and outlet conduits for said compartments, each of said conduits having convoluted portions about said shaft to prevent detrimental stresses within said conduits during movement of said cross-member.

5. A pump of the class described comprising two compartments, a communicating passage connecting said compartments, a metallic liquid in said compartments and said passage, a fluid conduit between said compartments, a common inlet conductor connected to said compartments, a common outlet conductor for said compartments, a rockable supporting member for said compartments, a source of energy for rocking said member, means for connecting said member to said source of energy for automatically actuating said member to cause a relative movement of said liquid for alternately effecting suction and compression in said compartments and valves in said inlet and outlet conductors operable to close during the compression period and open during the suction period, said inlet and outlet conductors being provided with convolutions disposed about the axial line of movement of said member to prevent detrimental stresses in said conductors during movement of said member.

In testimony whereof, I have hereunto subscribed my name this 15th day of February 1927.
